(57) **CLAIM**

The ornamental design for headset, as shown and described.

DESCRIPTION

FIG. 1 is a perspective view of a headset showing our new design, as viewed from the top and front;

FIG. 2 is a front elevational view thereof;

FIG. 3 is a back elevational view thereof;

FIG. 4 is a first side elevational view thereof;

FIG. 5 is a second side elevational view thereof;

FIG. 6 is a top plan view thereof; and,

FIG. 7 is a bottom plan view thereof.

1 Claim, 5 Drawing Sheets---
